UNITED STATES PATENT OFFICE.

EDWARD G. GERMER, OF ERIE, PENNSYLVANIA, ASSIGNOR TO GERMER STOVE COMPANY, OF ERIE, PENNSYLVANIA, A CORPORATION OF PENNSYLVANIA.

GAS-STOVE.

1,198,907.

Specification of Letters Patent. Patented Sept. 19, 1916.

Application filed December 16, 1914. Serial No. 877,517.

To all whom it may concern:

Be it known that I, EDWARD G. GERMER, a citizen of the United States, residing at Erie, in the county of Erie and State of Pennsylvania, have invented new and useful Improvements in Gas-Stoves, of which the following is a specification.

This invention relates to gas stoves and consists in certain improvements in the construction thereof as will be hereinafter fully described and pointed out in the claims.

More particularly the invention relates to gas heating stoves. In these stoves as ordinarily marketed there are three principal considerations, namely: the efficiency of the stove as a heater, its appearance or artistic effect especially when the stove is in use, and the protection from immediate contact with the flame.

The present invention is directed to improving a stove along these different lines as well as the details of construction which will appear more fully from the specification and claims.

The invention is illustrated in the accompanying drawings as follows:—

Figure 1 shows a front elevation of the stove, a part being broken away to the section line 1—1 in Fig. 2. Fig. 2 a section on the line 2—2 in Fig. 1. Fig. 3 a section on the lines 3—3 in Figs. 1 and 2.

The stove frame or case as shown is formed of sheet iron. It has a rear plate 1. The sides of the frame are formed from the same plate as the rear by bending the sides of the plate forming the back forward. The front edges of the sides are bent inwardly and the front plate 3 is secured to these edges in any convenient manner. The front plate has an opening 4 for the reflecting plate of the stove hereinafter referred to. A dish-shaped bottom plate 5 is provided and has openings 5^a for the admission of air around the edges. A top plate 1^a forms a joint with the top edges of the back, sides and front of the frame.

A burner 6 extends from side to side of the stove. It terminates in a mixer 7 and an ordinary gas valve 8 is arranged at the end 50 of the mixer. A fire back 9 is arranged directly back of the burner. This is supported by a metal plate 10 which extends across the stove. It has the lips 10^a at the top and bottom which secure the fire back and the flanges 10^b at the ends which are secured to

flue plates 12 at each side of the stove. A baffle plate 13 is arranged diagonally above the burner and extends from the top of the opening 4 to the upper part of the rear plate 1. It extends sidewise to the flue 60 plates 12. The baffle plate 14 extends between the flue plates 12 and from the top baffle 13 downwardly. The gases pass from the burner along the fire back and then are deflected by the plate 13 to the passage 65 between the rear of the plate 10 and the baffle 14. The gases then pass upwardly along between the baffle 14 and the rear plate 1 and are discharged through an opening 15.

The fire back has a series of projections 70 16. The burner has a series of jet openings 17 extending entirely along the fire back. Adjacent to each projection 16, however, there is massed added jet openings 19 so that the mass of flame envelops the projection 75 16 thus heating these projections to an incandescent state. The fire back is preferably of material, ordinarily fire brick which will readily glow under heat. By extending the jets along the burner, the burner may be 80 lighted through the lighter opening 20 at the side of the stove, the ignition being carried along by the jets 17.

A plate 21 is arranged under the burner and forms an air chamber 22 at the bottom 85 of the stove, the ends of this air chamber communicating with the flue 24 formed between the flue plate 12 and the side 2 of the stove. Air passes by the flue 24 to the chamber 25 formed above the baffle plate 13 and 90 thence out of openings 26 in the top of the stove. Openings 23 are arranged in the plate 21 directly under the burner so as to supply air for combustion.

A reflecting plate 27 is arranged in the 95 opening 4. This plate has a surrounding flange 28 and a depressed or inwardly extending portion 29, thus forming side walls 30, top wall 31 and bottom wall 32. The rear wall of the plate 27 has vertical slots 100 33 and the top and bottom walls have semi-circular openings 34 directly in front of the slots 33. PELLUCID closure pieces 35 are arranged in front of the slots 33. These are inserted by slipping the closure pieces upwardly in the slots 34 in the upper wall 31 and then lowering them into the openings 34 in the lower wall 32. The rear edges of the closure pieces when in place rest against the front face of the rear wall and are out 110

of contact with each other, leaving a strip of the plate 27 visible between them. The pellucid pieces 35 rest on the platform 21^a, this being an upwardly bent portion in the 5 plate 21. Openings 36 are arranged in the platform 21^a directly back of the pellucid pieces 35. These pellucid pieces are curved and formed of glass having the outer surface ground so as to give a translucent as 10 well as pellucid effect, thus the incandescent glow of the projection 16 is communicated from the pellucid pieces giving a very pleasing effect. At the same time a complete closure is provided for protection against 15 the flame. The plate 27 is preferably of white enamel both for appearance and for its effect as a reflector. The air passing up through the openings 36 insulates the pellucid pieces sufficiently to prevent their being so intensely heated from the burner as 20 to crack the glass. The stove is very efficient as a heater both by reason of the direct action of the gas and air and the reflection from the incandescent portions.

25 What I claim as new is:—

1. In a gas stove, the combination of a gas burner; an inclosed front comprising members of rigid pellucid material curved with a vertical axis and outstanding from the 30 portions of the front immediately adjacent to the edges of said members, said members being open toward the burner; and means for establishing a current of insulating air along the inner surfaces of said members. 35 2. In a gas stove, the combination of a burner; an inclosed front comprising a metal plate having vertical slots therein and a closure piece of pellucid rigid material bridging said slots, said closure piece being 40 curved with a vertical axis and protruding from said plate; and means for establishing a current of insulating air along the inner surface of said closure piece.

3. In a gas stove, the combination of a gas 45 burner; a metal front having openings therein; curved closure pieces for the openings, said closure pieces outstanding from the openings and being formed of pellucid material, said pieces being spaced apart exposing portions of the metal front between them.

4. In a gas stove, the combination of a gas 55 burner; a metal front having vertical slots therein; closure pieces of rigid pellucid material bridging said slots and curved with vertical axes and outstanding from said metal front; and means for establishing a current of insulating air along the inner surfaces of said pieces.

60 5. In a gas stove, the combination of a gas burner; a metal front having openings therein, said front being coated with a reflecting material; closure pieces bridging said openings and outstanding from said 65 front, said closure pieces being formed of

pellucid material adapted to reflect the rays from the burner onto said reflecting material.

6. In a gas stove, the combination of a gas burner; a metal front having a depressed 70 portion, the rear wall of which has vertical slots; and closure pieces of rigid pellucid material bridging said slots, said closure pieces being curved outwardly with vertical axes, the outer surfaces of the closure pieces 75 being within the plane of the stove front and outstanding from the rear wall of the depressed portion.

7. In a gas stove, the combination of a gas burner; a metal front having a depressed 80 portion forming top and bottom walls, said top and bottom walls having openings and the rear wall of said depressed portion having openings; and rigid pellucid closure pieces bridging the openings in the rear 85 wall abutting against the same and extending through the openings in the top and bottom walls.

8. In a gas stove, the combination of a gas burner; a metal front having a depressed 90 portion forming top and bottom walls, said top and bottom walls having openings and the rear wall of said depressed portion having openings; rigid pellucid closure pieces bridging the openings in the rear wall and 95 extending through the openings in the top and bottom walls, said closure pieces being open at the rear and curved with vertical axes; and means for establishing an insulating current of air along the backs of said 100 pieces.

9. In a gas stove, the combination of a gas burner; an inclosed front comprising members of rigid pellucid material curved with vertical axes and open at the rear; a fire 105 back at the opposite side of the burner, said fire back having projections opposite said members adapted to become incandescent from the flame from the burner; and means for establishing an insulating current of air 110 along the backs of said portions.

10. In a gas stove, the combination of a gas burner; a metal front coated with reflecting material and having openings therein; closure pieces for the openings formed 115 of pellucid material, said closure pieces being outwardly curved and outstanding from said front and open at the rear; and a fire back at the opposite side of the burner, said fire back having projections opposite said 120 pieces adapted to become incandescent from the flame from said burner.

11. In a gas stove, the combination of a fire back having vertical projections adapted to become incandescent from the flame 125 from a burner; a burner adjacent to the fire back adapted to mass its flame on said projections to bring said projections to a state of incandescence; a metal front having openings opposite said projections; and 130

closure pieces in said openings of pellucid material.

12. In a gas stove, the combination of a fire back having vertical projections adapted to become incandescent from the flame from a burner; a burner adjacent to the fire back adapted to mass its flame on said projections to bring said projections to a state of incandescence; a metal front having openings opposite said projections; and closure pieces in said openings of pellucid material, said closure pieces being outwardly curved with vertical axes.

13. In a gas stove, the combination of a fire back having vertical projections adapted to become incandescent from the flame from a burner; a burner adjacent to the fire back adapted to mass its flame on said projections to bring said projections to a state of incandescence; a metal front having openings opposite said projections; closure pieces in said openings of pellucid material, said closure pieces being curved with vertical axes and outstanding from the front; and a reflecting coating on the front adjacent to said closure pieces.

14. In a gas stove, the combination of a fire back having vertical projections thereon adapted to become incandescent from the flame from a burner; a burner having openings therein formed to mass its flame against said projections to bring said projections to a state of incandescence and to carry ignition from one end of the burner; an inclosed front comprising a metal plate having vertical slots therein adjacent to the

projections on the fire back; closure pieces curved with vertical axes of rigid pellucid material bridging said slots and outstanding therefrom; and means for establishing an insulating current of air along the backs of said closure pieces.

15. In a gas stove, the combination of rear walls, and side walls; a front plate having an opening therein; flue plates forming side flues in the stove; a top baffle plate forming a top chamber in the stove; a burner arranged across the stove from side to side; a fire back back of the burner supported by the flue plates, said fire back having vertical projections thereon adapted to become incandescent from the flame from said burner; a closure plate in the opening in the front of the stove, said closure plate having a depressed rear portion forming top and bottom walls, the rear wall of said closure plate having vertical slots and the top and bottom walls having openings in front of said slots; and closure pieces of pellucid material arranged in said openings and bridging said slots, said closure pieces being curved with vertical axes and outstanding from the rear walls of said closure plate.

In testimony whereof I have hereunto set my hand in the presence of two subscribing witnesses.

EDWARD G. GERMER.
